SEAL FOR CONTAINERS

Jesse E. Roach, Forest Hills, N. Y.

Substitute for abandoned application Serial No.
34,866, August 6, 1935. This application February 21, 1939, Serial No. 257,597

11 Claims. (Cl. 229—5.5)

This invention relates to improvements in closures and seals for containers and more particularly it pertains to closures for sealing commercial packages of materials of a semi-fluid nature.

5 This application is a substitution application filed in lieu of applicant's forfeited application, Serial No. 34,866, filed August 6, 1935.

The closure and seal of the present invention, while capable of use in many other connections, 10 particularly lends itself to containers of the liquid proof paper or cardboard type and renders such containers adaptable to commercial use, in which use, because of inability to form an effective seal, this type of container has not heretofore 15 found an extensive use.

Many commodities such for example as jellies, jams and the like have a decided tendency to develop mold if all air is not excluded from the container in which they are packed thereby producing an unsightly appearance.

20 Because of the afore-mentioned difficulties and disadvantages, containers of liquid proofed paper and similar materials, although highly desirable for many other reasons, have not found extensive 25 use for the purposes described, and it is the object of this present invention to provide a new and improved construction of closure and seal which will effectively exclude air and prevent mold, which closure and seal are particularly 30 adapted for use in connection with containers formed of liquid proofed paper and the like.

It is a further object of the present invention to provide a closure and seal for containers particularly of the afore-mentioned type in which, 35 when the seal is closed, there will be no space in which air could possibly accumulate, the sealing element being in contact throughout on one side with the material within the container and upon the other side with sufficient sealing medium to 40 effect a complete exclusion of air.

45 It is a further object of the invention so to construct the seal that the material within the container will not be subjected to shifting or moving within the container during transportation, which is an important feature in connection with certain commodities of which jelly is one very good example, since it prevents the breaking up of the pectin cells and thereby prevents the jelly from returning to syrup.

50 It is still a further object of the invention so to construct the seal that it may be readily removed without damage to the contents of the receptacle.

With the above and other objects in view reference will be had to the accompanying drawing, 55 in which:

Figure 1 is a perspective view of a container constructed in accordance with one form of the present invention.

Figure 2 is a top plan view thereof.

Figure 3 is an enlarged detail sectional view partly broken away taken substantially on the line 3—3 of Figure 2.

Figure 4 is a detail fragmentary transverse sectional view illustrating the seal in operative position to close the container.

Figure 5 is a detail fragmentary sectional view of a modified form of the invention.

Figure 6 is a detail perspective view showing one form of sealing element employed.

Figure 7 is a detail perspective view of a closure member employed, and;

Figure 8 is a plan view illustrating a modified form of sealing member.

Referring specifically to the drawing, the reference numeral 10 designates a container which, 20 in the present embodiment of the invention, is illustrated as formed from liquid proofed paper or similar material. In this embodiment the container is shown as of cylindrical form, but it is to be understood that the shape thereof may 25 be of any form desired. The side walls of the container, preferably taper and near the upper or open end of the container, the side walls are formed with a bead 11, which in turn provides 30 an internal channel 12 extending around the inner face of the side walls.

The closure medium is designated by the reference character 14. It consists of a disk like member formed preferably from two plies 15 and 16 of paper or similar material water proofed in 35 any preferred manner. These two plies of material are secured together in any desired manner throughout the major portion of their areas. Their peripheral edges are, however, spaced from each other, as best illustrated in Figures 3 and 4

40 of the drawing, and this spacing of the peripheral edges of these members provides a peripheral channel designated 17 in the drawing. The side walls of this channel 17, which side walls comprise the spaced edges of the disk like member, are provided with perforations 18 and 19, the first mentioned being formed in the upper ply, the second mentioned being formed in the lower ply. The perforations 18 and 19 are staggered with respect to one another and the specific purpose of these 50 perforations will be hereinafter more fully set forth.

The disk like member 14 is provided preferably by embossing with a channel 20 on its inner face. This channel 20 is spaced from the peripheral 55

edge of the disk like member 14 and the outer side walls of this channel form the inner or bottom wall of the channel 17. The formation of this channel 20 produces an upstanding annular bead 32 extending entirely around the disk like member 14 and this construction provides an annular space or pocket 35 between the outer side walls of the beads and the adjacent side walls of the container 10.

10 The reference numeral 40 designates a sealing element which is adapted to be inserted within the open end of the container after the disk like member 14 has been sealed therein. This sealing element 40 is preferably of a size to snap 15 into the channel 12 and be retained therein, and the proportions of the several parts will be such that when this sealing element 40 is in position it will rest upon the annular bead 32 of the disk like member 14, as shown in the drawing, to provide 20 a space 42 between the disk like member and the sealing element. This space will be sufficient to house a circular or other descriptive matter which is illustrated in Figure 3 at 43. The sealing element, as shown in Figure 2, is provided 25 with two lines of perforations 46 to provide a removable section 47, which section has one free end 48 by which it may be grasped and severed from the sealing element to provide two removable sections 49 and 50. The section 47 is provided 30 with a slot 51, and this slot provides for the insertion of the circular or descriptive matter 43 after the sealing element has been positioned as described.

35 The operation and method of use will now be described.

The commodity to be fed and stored is designated by the reference character 60. It is filled into the container to the desired level after which the disk like member is inserted in the open end 40 of the container and pressed downwardly upon the commodity 60. The pressure applied to the disk like member causes the commodity to rise and fill the annular channel 20 and a portion of the commodity will pass through the perforations 45 19 into the annular channel 17. If the commodity is fed in a warm or heated state, upon cooling and contraction thereof the disk-like member will follow the same downwardly so that the annular channel 20 will at all times remain 50 filled, and there will be no voids between the upper level of the commodity and the walls of said annular channel. Also, under such conditions, the openings 19 will be sealed by the commodity, thus preventing the entrance of air 55 through the interior of the container behind the disk like member 14. After the disk like member 14 has been positioned, a sealing medium 59, of which paraffin wax is one good example, is poured in hot liquid state into the space or pocket 35 until it reaches the level of the top of the bead 32, after which and while this sealing medium is still hot and in liquid state, the sealing element 40 is positioned so that as the sealing medium cools, the element 40 will be sealed in contact with the 60 annular bead 32 throughout its entire length. When the sealing medium is poured into the space or pocket 35 it passes through the perforations 18 into the annular channel 17, filling the same, and this portion of the sealing medium 59 together with that retained in the space or pocket 70 35 forms an effective seal between the disk like member 14, the side walls of the container, and the sealing element 40, which will exclude all possibility of air entering the container.

75 By practicing the method just described, the

disk like member 14 in effect floods upon the commodity 60 and will always remain in contact therewith. By reason of this fact transportation of a number of containers thus filled will not permit movement of the commodity within the 5 container and will thus preserve its consistency and prevent its return to syrup when such commodity is of the character or type which results in such action.

To gain access to the container it is only necessary to tear out the section 47 of the element 40, remove the circular 43, place the fingers or a tool under the inner edges of the two sections 49 and 50 whereby they may be bodily removed. The element 40 being removed a sharp instrument such as a knife is run around the edge of the sealing medium 59 and the element 40 may then be bodily removed, which action brings with it the loosened sealing medium leaving the upper surface of the commodity clear and clean. 20

Means is provided for lifting the element 40 from the container as described, and this means consists preferably of a pair of wing like members 70 and 71 which are formed by severing the upper ply 15 of the disk like member 14 as indicated 25 at 72. After the sealing element 40 has been removed, these wing like members may be bent upwardly to a position where they may be gripped to remove bodily the disk like member 14.

In Figure 8 I have illustrated a slightly modified form of sealing element. In this form the sealing element is designated 40' and is provided with a central opening such as 42' sufficiently large to permit of the insertion of a finger thereinto and pull the element 40' to remove the same 35 from the container. In this form the element 40' is not torn or separated into separate elements as is the element 40 in the previously described form of the invention.

In Figure 5 I have shown a still further modified form of the invention in which the sealing element, designated 60', takes the form of a disk like member having an upstanding flange portion 61' and depending flange portion 62'. The body portion of the sealing element 65 is so constructed and arranged as to force a portion of the depending flange 62' into the annular channel 12 in the side wall of the container when the sealing element is placed in position. In this form of the invention the sealing element may be provided either with the removable section 47 as shown in Figure 3 or with the opening as illustrated in Figure 8 of the drawing to facilitate its removal from the container.

From the foregoing it will be apparent that the present invention provides an effective seal for containers in which the several objects recited are accomplished and, although the invention has been herein illustrated in certain specific forms it is to be understood that it is not to be limited to the constructions herein shown and that it may be practiced in other forms without departing from the spirit thereof.

Having thus described the invention what is claimed as new, is:

1. A closure for containers comprising a disk like member adapted for insertion into and closing the open end of a container, said disk like member having a peripheral channel having its open side closed by the side walls of the container when the disk like member is in position therein, the side walls of said channel being perforated.
2. A closure for containers comprising a disk like member adapted for insertion into and closing the open end of a container, said disk like 75

member having a peripheral channel having its open side closed by the side walls of the container when the disk like member is in position therein, the side walls of said channel being perforated, 5 said disk like member also having an annular channel in its inner face, said annular channel being spaced from the peripheral edge of the disk like member.

3. A seal for containers comprising a disk like member having a peripheral channel the side walls of which are perforated, said peripheral channel being closed by the side walls of a container when the disk like member is positioned in the open end of a container and a separate sealing member adapted for insertion into the open end of the container after the disk like member has been positioned therein.

4. A closure for containers comprising a disk like member adapted for insertion into the open end of a container, said disk like member having an annular channel in its inner face, said channel forming an upstanding annular bead on the outer face of the disk like member, said bead being spaced from the peripheral edge of the disk like member, and a separate sealing element insertable into the open end of the container, said separate sealing element forming with the first disk like member, the annular bead and the side wall of the container, an annular pocket for the reception of a sealing medium, and a sealing medium in said annular pocket.

5. A closure for containers comprising a disk like member adapted for insertion into the open end of a container, said disk like member having a peripheral channel having its open side closed by the side walls of the container when the disk like member is in position therein, an annular bead on the outer face of the disk like member, and a separate sealing element insertable into the open end of the container, said sealing element being spaced from the disk like member by the said annular bead to form a pocket between the disk like member and the sealing element within the confines of said annular bead.

45 6. A closure for containers comprising a disk like member adapted for insertion into the open end of a container, said disk like member having a peripheral channel having its open side closed by the side walls of the container when the disk like member is in position therein, an annular bead on the outer face of the disk like member, a separate sealing element adapted to rest on said annular bead and spaced from the disk like member by said annular bead to provide a pocket between the disk like member and said separate sealing element within the confines of the annular bead, said separate sealing element having an opening therein to provide access to said pocket.

7. A closure for containers comprising a disk like member adapted for insertion into the open end of a container, said disk like member having a peripheral channel having its open side closed by the side walls of the container when the disk like member is in position therein, an annular bead on the outer face of the disk like member, a separate sealing element adapted to rest on said annular bead in spaced relation to the disk like member, and means for removing said separate sealing element from the open end of the container.

70 8. A closure for containers comprising a disk like member adapted for insertion into the open

end of a container, said disk like member having a peripheral channel having its open side closed by the side walls of the container when the disk like member is in position therein, an annular bead on the outer face of the disk like member, 5 a separate sealing element adapted to rest on said annular bead in spaced relation to the disk like member, and means for removing said separate sealing element from the open end of the container, said last mentioned means comprising 10 a wing member adapted to be bent outwardly to provide hand grips.

9. A closure for containers comprising a disk like member adapted for insertion into the open end of a container, said disk like member having 15 a peripheral channel having its open side closed by the side walls of the container when the disk like member is in position therein, an annular bead on the outer face of the disk like member, a separate sealing element adapted to rest on said 20 annular bead in spaced relation to the disk like member, and means for removing said separate sealing element from the open end of the container, said last mentioned means comprising a 25 removable section adapted to be severed from the separate sealing element to divide it into separately removable sections.

10. A closure for containers comprising a disk like member adapted for insertion into the open end of a container, an annular bead on the outer 30 face of said disk like member, a separate sealing element adapted to rest on said annular bead in spaced relation to the disk like member to form a pocket between the disk like member and the separate sealing element and within the confines 35 of the annular bead, and a removable section in said separate sealing elements, said removable section having an opening therein to provide access to said pocket.

11. A closure and seal for containers comprising 40 a disk like member for closing the open side of a container, said disk like member comprising two relatively thin sections secured together throughout their major area, the peripheral edges of said sections being spaced from each other 45 thereby to provide a peripheral channel open on the peripheral edge of the disk like member, the opposite side walls of which are perforated with the perforations in each wall staggered with relation to the perforations in the other side wall 50 of the channel, an annular channel upon the inner face of said disk like member, said annular channel being spaced with relation to the peripheral edge of the disk like member with its outer wall forming the inner wall of said peripheral 55 channel, a sealing element, said disk like member and said sealing element being so constructed and arranged that when placed in the open side of a container to close the same, the sealing element rests upon the inner annular channel of 60 the disk like member with the peripheral edges of the disk like member and the sealing element engaging the side walls of the container thereby to form an annular space enclosed by the side walls of the container, one of the walls of the 65 peripheral channel, the outer wall of the annular channel and the sealing element, and a sealing medium filling said annular space and extending through the perforations in one of the side walls of the peripheral channel into said 70 annular channel.
